UNITED STATES PATENT OFFICE.

GEORGE P. BEDFORD, OF NEW YORK, N. Y.

DESIGN FOR A CLOCK-CASE.

SPECIFICATION forming part of Design No. 30,772, dated May 16, 1899.

Application filed April 7, 1899. Serial No. 712,183. Term of patent 3½ years.

To all whom it may concern:

Be it known that I, GEORGE P. BEDFORD, a citizen of the United States, residing at New York, in the county and State of New York, § have invented and produced a new and original Design for a Clock-Case, of which the following is a specification, reference being had to the accompanying drawings, forming part thereof, in which—

10 Figure 1 is a plan, and Fig. 2 an elevation, illustrating my new design; and Fig. 3, a cross-section of the same.

As shown in the drawings, the leading or material features of my design consist of a 15 hollow annular body or ring with annular beads adjacent to the upper and under surface and parallel sides extending down from the upper bead to meet inclined surfaces extending up from the lower bead.

a represents an upper flat surface, and *b* the 20 upper annular bead. The parallel sides are shown at *c* and the lower annular bead at *d*, and the inclined surfaces *e* extend up from the lower annular bead *d* to the parallel sides *c*. From the under edge of the annular bead *d* 25 a flat surface *f* extends inward, and the base of the hollow annular body or ring is made with a rib *g*.

What I claim is—

The design for a clock-case as herein shown 30 and described.

Signed this 1st day of April, 1899.

GEORGE P. BEDFORD.
